UNITED STATES PATENT OFFICE.

MICHAEL HEYMAN, OF CINCINNATI, OHIO.

NECKWEAR.

1,137,486.

Specification of Letters Patent   Patented Apr. 27, 1915.

Application filed August 8, 1914. Serial No. 855,718.

To all whom it may concern:

Be it known that I, MICHAEL HEYMAN, a citizen of the United States, and a resident of the city of Cincinnati, in the county of 5 Hamilton and State of Ohio, have invented certain new and useful Improvements in Neckwear, of which the following is a full, clear, and exact description, reference being had to the accompanying drawings, forming 10 part of this specification.

The object of my invention is to improve the construction of neckties, such as the four-in-hand, Ascot, string or other style of ties used with turn-down collars, to prevent 15 the tie from sticking in the collar fold as it is drawn into position for tying and to cause it to slide easily under the collar.

I accomplish this result by that certain 20 novel construction and arrangement of parts to be hereinafter particularly pointed out and claimed, whereby the wearing surface for the neck portion is reinforced on both 25 sides of the tie and this reinforcement is combined with the goods of the tie proper so as to present on both sides a comparatively frictionless surface when it is sought to slip the tie along the fold of the collar.

In the drawings, Figure 1 is a plan view 30 of the goods from which the tie is made, showing the reinforcing strips for the neck band. Fig. 2 is a similar view after the first fold is made. Fig. 3 is a plan view of the completed tie. Fig. 4 illustrates a modification of the reinforcing pieces. Fig. 5 is a 35 plan view after making the first fold in the modified construction. Fig. 6 is a similar view of the construction complete.

I have illustrated my invention in connection with the ordinary four-in-hand tie, 40 although it will be understood that the same is applicable to any variety of tie intended to encircle the neck for tying in front. I have illustrated substantially only the neck band portion of the tie, as my invention relates 45 to this portion of the scarf, and I have shown merely a portion of the tying part and of the ends.

In constructing my four-in-hand tie, I cut the goods 1 of the width and length for 50 the ordinary tie. Before folding and seaming together the side edges of the neck and tying portions I secure across, preferably in a diagonal direction, strips 2, 2, of any suitable material, to provide a reinforcement 55 for the neck portion. These strips are

sewed to the goods on the line 3, 3. Two strips can be used folded diagonally across each other as shown, or the strips may be cut in sections and each diagonal piece can be a separate piece. These reinforcing strips 60 extend only through the neck band portion, and the tying portions of the scarf and the loose ends are not provided with a reinforcement. It will be noted that with the diagonal strips secured in place, portions 4, 65 4, of the goods are not covered. Instead of using comparatively narrow strips, oblong or square pieces 5, 5, may be in a similar way secured by the stitches 7, 7, to the goods, leaving portions 6, 6, exposed, all as illustrated in Fig. 4.

It will be understood that these reinforcing strips are secured to the goods on the right or finished side of the fabric. Then the fabric is folded lengthwise along the 75 middle line and the edges seamed together by the line of stitches 8, both through the neck and tying portions of the scarf, the right side of the goods being folded inwardly, so that the tie when the sides are 80 secured together is wrong side out. The tie is then turned right side out and the seam 8 brought to the middle of the tie, and then the reinforcements and the folds of the tie are secured together by a triple row of 85 stitches 9, 10 and 11.

Where the square reinforcing pieces 5 are applied, as shown in Fig. 4 in diamond shape, the same method of construction is employed. The side edges are brought over 90 and secured together by a seam 12; then the tie is turned right side out and the seam line brought to the middle and then the triple row of stitches 13, 14 and 15 are employed to secure the reinforcement and the 95 goods at the neck portion.

With any quality of material, but especially with the finest of fabrics, silk and the like, the neck portion of the scarf is made much stronger and more durable than 100 where a reinforcing strip is attached upon one side only of the tie. Heretofore it has been sought to provide a slip tie by constructing the neck band portion of thinner material, or by stiffening the neck band 105 portion with sizing, or by cutting away one of the folds of the tie and inserting a reinforcing strip.

In all these constructions, one side of the tie at the neck band portion is of the origi- 110

nal fabric, and the tendency of this side to stick when it was sought to be drawn through the folded collar is not affected by any of the older constructions. I have found that with the reinforcement on both sides, or the duplex reinforcement with the triple line of stitches permanently securing the reinforcement and the longitudinal folds of the tie together, a much superior construction is provided, and the tendency to bind is entirely overcome.

Having thus described my invention, what I claim as new and desire to secure by Letters Patent, is:—

- 15 1. In a necktie of any desired fabric, a reinforcing strip of any desired fabric sewed diagonally on the fabric of the tie at the neck portion thereof, with the fabric together with the strip folded on itself to form a narrow neck band, with the reinforcing portion outside.
- 20 2. In a necktie, comprising two tying ends and an intermediate portion for encircling the neck, a reinforcing strip secured across the fabric, with the fabric folded on itself to form a narrow neck band and with the reinforcing strip on both sides of the band, and a triple line of stitches in parallel lines extending the length of the reinforced por-
- 25

tions securing the band folds and reinforcements together.

3. In a necktie, of any desired fabric, a reinforcing strip secured across the fabric at the neck portion thereof, with the fabric folded on itself to form a narrow neck band and with the reinforcing strip on both sides of the band having non-reinforced portions of the fabric intermediate the reinforced portions, and a triple line of stitches in parallel lines extending the length of the reinforced portions securing the band folds and reinforcements together.

4. In a necktie, comprising two tying ends and an intermediate portion for encircling the neck, a reinforcing strip secured across the fabric in diagonal lines crossing each other, with the fabric folded on itself to form a narrow neck band and with the reinforcing strip on both sides of the band, and a triple line of stitches in parallel lines extending the length of the reinforced portions securing the band folds and reinforcements together.

MICHAEL HEYMAN.
